COMBINED VALVE ACTUATOR AND DISPENSING HEAD FOR AN AEROSOL CONTAINER

Theodore Andrew Beck, Andover, Mass., assignor to Scovill Manufacturing Company, Waterbury, Conn., a corporation of Connecticut

Filed Apr. 9, 1969, Ser. No. 16,639

Term of patent 14 years

Int. Cl. D9—02

U.S. Cl. D9—258

Fig. 1.

Fig. 2.

Fig. 4.

Fig. 3.

FIG. 1 is a perspective view of a combined valve actuator and dispensing head for an aerosol container embodying my new design;

FIG. 2 is a top plan view;

FIG. 3 is a side elevational view; and

FIG. 4 is a longitudinal sectional view taken through FIG. 2.

I claim:

The ornamental design for a combined valve actuator and dispensing head for an aerosol container, substantially as shown.
